(57) **CLAIM**

The ornamental design for a massage stick, as shown and described.

DESCRIPTION

FIG. 1 is a top plan view of my new design.

FIG. 2 is a front view.

FIG. 3 is a back view.

FIG. 4 is a left side view. The right side view is a mirror image of the left side view.

FIG. 5 is a perspective view; and,

FIG. 6 is a bottom view.

The massage stick is symmetrical about its lateral centerline and the handles on either end are the same. The back, top and bottom of the handle are smooth surfaces and the roller between the handles is cylindrical.
